UNITED STATES PATENT OFFICE.

WILLIAM D. SHAFFER, OF BREA, CALIFORNIA, ASSIGNOR OF ONE-THIRD TO E. J. WILLIAMS, OF WHITTIER, CALIFORNIA, AND ONE-THIRD TO GEORGE S. FOSNAUGH, OF COMPTON, CALIFORNIA.

OIL-WELL PACKING HEAD.

Application filed October 10, 1925. Serial No. 61,682.

This invention relates to a packing device for use in connection with oil wells to control gas pressure developed in drilling.

An important object of the invention is to provide an improved device for supporting in position an inner string of casing upon an outer string and for forming between the casings a gas tight joint.

A further object is to provide a device that will effectually withstand high gas pressures oftentimes encountered in the drilling of oil wells, and which is especially adapted for use in connection with long heavy strings of tubing.

A still further object is to provide a casing head in which the inner string is supported by the outer string in such manner as to effectually sustain the ultimate strength of the casing coupling threads.

Still another object is to provide a packing head construction in which the inner supported string of casing or tubing can be readily set, or "landed" with a minimum loss of stretch.

A further object is to provide a packing head having packing means separate from the casing supporting means in order that the packing may be quickly adjusted or renewed without disturbing the casing.

Other objects and advantages will be apparent as the description proceeds, reference being had to the drawings accompanying the same in which:

Fig. 1 is an elevation of the casing head packer attached to the upper end of a well casing, parts being in section to more clearly disclose the relation of the parts.

Fig. 2 is a plan view of the packer.

Fig. 3 is a detail vertical section through a portion of the packer, taken on line 3—3 of Fig. 2.

Referring now more particularly to the drawings, and especially to Figs. 1 and 3, 5 designates a cylindrical sleeve exteriorly threaded on its lower end for engagement with the internally threaded upper end of string of outer well casing 6. Sleeve 5 is provided in its cylindrical wall with the usual gas outlet pipe lines 7 controlled by valves (not shown). The upper end of sleeve 5 is provided with an internal seat 8 for the reception of a metal packing supporting ring 9 preferably divided for the purpose of easy assemblage. This ring is

provided on its upper edge with an internal 55 annular seat 10 in which is seated a packing ring 11 formed of an elastic material. The internal diameter of ring 9 is of slightly larger diameter than the outside diameter of the inner casing 12 in order that no binding 60 action may occur when in place.

Secured in screw threaded engagement with the upper threaded end of sleeve 5 is a ring 13 that forms a member of a packing gland. Interposed in the space between this 65 ring and the casing coupling 14 is a packing ring 15 that serves to form a gas tight joint between the coupling and ring when the packer is assembled. Disposed upon packing ring 15 is a gland or follower 16 having 70 on its upper end an annular external flange 17. This flange is connected by a series of bolts 18 whose lower ends engage a circular flange 19 that surrounds the sleeve 5 of the packer and bears against an annular shoulder 20 formed on said sleeve. By tightening the nuts 21 of the bolts 18 the gland or follower is forced downwardly against the packing ring 15 to compress the same to completely fill the space between the ring 13 and 80 the casing coupling.

It will be understood that the method of supporting an inner string of casing on an outer string by employing split or divided packing rings with a rubber packing surrounding the casing is old in the art, but the heavy weight of long strings of casing now generally employed in the drilling of oil wells has oftentimes resulted in the rubber packing squeezing the casing so that its internal diameter is greatly reduced at that point. This is objectionable in that it interferes with or prevents the passing of tools inside the casing. By my method of packing outside of the casing coupling these 90 unto-ward and objectionable features are obviated.

By using a small packing ring 11 immediately under the coupling a yielding cushion is provided for any unevenness of the casing coupling, and not enough packing that can 100 readily crush the pipe. The packing 11 disposed under the coupling is found to be quite essential in the distribution of the load, for if the coupling rested directly on the steel ring 9 and the underside of the coupling did 105 not bear perfectly around its annular edge the weight of the casing would be shifted to one side of the coupling, and thereby im-

pose a severe strain on the threads of the coupling, which would tend to cause the casing to strip the threads and drop.

It frequently happens when "setting" an inside string of casing that the lower end is oftentimes cemented fast or becomes frozen to the formation. In such cases it is then customary to pull the casing until the desired amount of stretch in the casing is attained when the casing is secured. By forming the stuffing box so that the sleeve 13 can be readily separated from the body 5 at the seat, the packing 11 and the ring 9 can be readily slipped into position and the coupling 14 is set in position. At the same time very little of the stretch attained as heretofore noted is lost as compared with the stretch lost if the coupling had been raised to the top of the stuffing box in order to insert the split rings and packing under the coupling.

What I claim is:

1. A casing head construction comprising a tubular body member adapted to be detachably secured to the upper end of a string 25 of well casing, said body member provided with an internal seat adjacent its upper end, a metallic packing supporting ring having an internal annular seat disposed upon the seat of said body member, a packing ring

mounted on the metallic ring disposed upon the annular seat of the metal ring for cushioning a coupling of an inner string of tubing, a circular sleeve detachably secured to the upper end of the body member, a second packing ring disposed within said sleeve 35 to pack the space between the tubing coupling and the circular sleeve, a gland follower disposed upon the second named packing ring, and means to move the gland follower to compress the last named packing ring. 40

2. A casing head construction comprising a tubular body member adapted to be detachably secured to the upper end of a string of well casing, said body member being provided with an internal seat adjacent its upper 45 end, a metallic supporting ring disposed upon the seat of said body member, a circular sleeve detachably secured to the upper end of the body member, a packing ring disposed within said sleeve to pack the space between the 50 tubing coupling and the circular sleeve, a gland follower disposed upon the packing ring, and means to move the gland follower to compress the packing ring.

In witness that I claim the foregoing I 55 have hereunto subscribed my name this 3rd day of August, 1925.

WILLIAM D. SHAFFER.
